(57) **CLAIM**

The ornamental design for a sleeve for fiber optic connector, as shown and described.

DESCRIPTION

FIG. 1 is a front side perspective view from the top of a sleeve for fiber optic connector showing our new design; FIG. 2 is a front side view of the sleeve for fiber optic connector shown in FIG. 1;

FIG. 3 is a back side view of the sleeve for fiber optic connector shown in FIG. 1;

FIG. 4 is a left side view of the sleeve for fiber optic connector shown in FIG. 1;

FIG. 5 is a right side view of the sleeve for fiber optic connector shown in FIG. 1;

FIG. 6 is a top side view of the sleeve for fiber optic connector shown in FIG. 1;

FIG. 7 is a bottom side view of the sleeve for fiber optic connector shown in FIG. 1;

FIG. 8 is a front side perspective view from the top of a sleeve for fiber optic connector showing our new design;

FIG. 9 is a front side view of the sleeve for fiber optic connector shown in FIG. 8;

FIG. 10 is a back side view of the sleeve for fiber optic connector shown in FIG. 8;

FIG. 11 is a left side view of the sleeve for fiber optic connector shown in FIG. 8;

FIG. 12 is a right side view of the sleeve for fiber optic connector shown in FIG. 8;

FIG. 13 is a top side view of the sleeve for fiber optic connector shown in FIG. 8; and,

FIG. 14 is a bottom side view of the sleeve for fiber optic connector shown in FIG. 8.

The broken lines shown represent portions of the sleeve for fiber optic connector that form no part of the claimed design.

1 Claim, 10 Drawing Sheets
